UNITED STATES PATENT OFFICE.

JOHN L. BECK, OF SPRINGFIELD, MASSACHUSETTS.

CHECK VALVE FOR FLUSHOMETERS.

Application filed January 20, 1920. Serial No. 352,666.

To all whom it may concern:

Be it known that JOHN L. BECK, a citizen of the United States, residing at Springfield, in the county of Hampden and State of Massachusetts, has invented certain new and useful Improvements in a Check Valve for Flushometers, of which the following is a specification.

This invention relates to a check valve for a flushometer which is a device for controlling the supply of water to water closet bowls, and the primary object I have in view is to provide an article of the character set forth which is simple in construction, positive in action and which is practically or nearly noiseless. In Letters Patent No. 1,171,085 issued to me February 8, 1916 is an article of the same general kind and the present device is in the nature of an improvement of that described by the patent and others of the same type which it is of course not necessary for me to more particularly identify.

In the drawing accompanying and forming a part of the present specification I have shown in detail a form of embodiment of the invention which to enable those skilled in the art to practice the same will be set forth fully in the following description. I am not restricted to this particular disclosure. I may depart therefrom in several respects within the scope of the invention defined by the claims following said description.

Referring to said drawing:

Fig. 1 is a vertical section of the flushometer.

Fig. 2 is a cross sectional view in top plan.

Fig. 3 is a vertical section on the line 3—3 of Fig. 2.

Fig. 4 is a perspective view of a valve member.

Like characters refer to like parts throughout the several views.

The article set forth herein is what is known in my prior patent as a "flushometer". Sometimes it is termed a "flush valve". Obviously it involves a valve of suitable character. When this valve is opened a supply of water is caused to flow to a part ordinarily a water closet bowl.

The flushometer comprises in its makeup a casing such as that denoted in a general way by 2 the base portion 3 of which has an internally-threaded hub or boss 4 to receive the pipe 5 for the supply of water to the service pipe 6 when the valve or valves here-

inafter described are opened. The supply pipe 5 as shown is fitted as by threading into the hub or boss 4 of the base portion 3 while the service pipe 6 is fitted as by threading to the hub or boss 7 on the opposite side of said base portion 3. The base portion 3 is divided by a wall or partition 8 situated between the supply and service pipes 5 and 6 respectively this wall or partition 8 having an opening or port 9 controlled by valves as I will hereinafter explain. When a valve or both valves are opened, water will flow from the supply pipe through the port 9 to the service pipe 6 and be discharged as required.

The valve mechanism as well as the other parts of the device may vary decidedly in that the invention covers certain broad relations. I will however describe a valve mechanism which meets my requirements. This mechanism involves a primary valve as 10 connected in some suitable way to the lower end of the stem 11. The primary valve closes against the central opening in the secondary valve 12. It should be noted that while I call the valves 10 and 12 primary and secondary, I do not necessarily mean to imply that one is subordinate to the other. As a matter of fact, it will be clear, that it is not always necessary to employ them both and there may be times in fact where valve mechanism of an entirely different character could be utilized. The primary valve 10 when closed, fits against a seat at the lower side of the central opening of the secondary valve 12 the latter when closed fitting against the wall or partition 8 as shown clearly in Fig. 1. The stem 11 as shown is furnished with three radial arms 13 near the lower end thereof and constituting a spider or actuator.

It will be assumed that a supply of water is desired. In this event the stem 11 is thrust downward thereby carrying the valve 10 therewith and uncovering the port or opening of the secondary valve 12 thus permitting the flow of water from the main or supply pipe 5 through the central opening of the valve 12 and obviously into the service pipe 6. On the further downward movement of the stem 11 the arms 13 which fit in the opening 9 will directly engage the valve 12 and cause the latter to uncover said opening and to admit a further supply of water therethrough. The arrows in Fig. 1 show the direction of flow of the water from the main or pipe 5 to the service pipe

6. The stem 11 extends through the gland 14 in the top of the base portion 3 of the casing 2.

The casing 2 comprises a chamber as 15 the bottom of which constitutes the top of the base portion 3 and the valve stem 11 extends through a gland 16 in said top. This chamber is adapted to contain a liquid of suitable kind such for instance as oil.

10 In said chamber 15 is vertically movable or slidable a piston or plunger as 17 of practically cupped form and which may be peripherally packed as shown. This piston or plunger 17 moves with the stem 11 the latter 15 having an enlarged portion 18 extending through a central opening of the piston and having at its lower side a collar or flange 19 fitted against the under side of the piston or plunger. The upper part of this enlarged portion 18 is threaded to receive the nut or washer 20 which bears against the upper face of the piston or plunger and thus provides a simple means for connecting the piston or plunger with the stem for 25 movement therewith.

Around the stem 11 is the coiled spring 21 bearing at its upper end against the piston or plunger and at its lower against the bottom of the chamber 15 the function of 30 the spring being to retract or move upward the piston or plunger. In the top 22 of the chamber 15 is a filling opening 23 normally closed by the screw plug 24 by taking out which oil or equivalent may be supplied to 35 the interior of the chamber 15 when desired, by way of said opening 23.

The body of the piston or plunger 17 has in its upper side a short distance from the center thereof the cylindrical cavity 25, the 40 bottom of which is concaved as at 26 and from the cavity leads the port or opening 27. This cavity or socket 25 receives in it the valve 28 convexed on its under side to fit solidly against the concaved surface 26 when 45 said valve is closed at which time the valve closed the opening or port 27. Upward or opening movement of the valve 28 is limited by the overhanging portion of the nut or washer 20 to which I have already referred, 50 at which time the valve 28 is open its maximum extent, having been opened by the pressure of liquid against its concaved surface 26 when the plunger or piston 17 is pushed downward to flush as I will later 55 set forth. This valve is of triangular form in cross section being practically of an equilateral form, its top being somewhat flattened. It freely or easily fits the cavity or chamber 25. Said valve 28 has centrally 60 in its upper side thereof the opening 29 into which lead the three ports 30 from the exterior surface of the valve.

It will be assumed that the piston or plunger 17 is at the limit of its upward 65 movement and that it is thrust downward,

as I will later explain. On such downward movement the pressure of the liquid in the chamber 15 below the valve, passing through the port 27 will strike the under convexed surface of the valve and will instantly open 70 or raise it as the piston moves downward, the oil or equivalent liquid flowing through the ports 30 and out of the opening 29 to the upper side of the chamber 15 or above the piston 17 therein, this continuing until 75 the piston reaches the downward limit of its movement. As the piston moves up, liquid above the piston will at once close the valve 28 or cause its convexed surface to seat against the concaved surface 26 and thus 80 close the port 27. During the downward movement of the piston the valves 10 and 12 one or both to which I have already referred, will open for purpose of flushing. On the upward movement of the piston the liquid 85 is by-passed from above the piston to below it, the closing or ascent of the piston being a comparatively slow one.

Chamber 15 may have a by-pass passage 32 flow of liquid through which is governed 90 by the valve 33.

To effect the action of the stem and therefore of the valve mechanism to obtain a supply of water a handle as 42 may be provided the handle having a shank 43 extending therefrom into the cap 41 and having in the cap a convexed foot 44 which is adapted to engage the upper end of the stem 11. The cap 41 is furnished with an inwardly extending flange or lip 45 which 100 overlies the foot 44 and thus holds the handle 42 and its shank in proper position, obviously limiting the upward movement of the handle.

To secure a supply of water to the service 105 pipe 6 the handle 42 is grasped and thrust downward thereby causing the lowering of the stem 11 and the resultant opening of the primary valve 10. Should the downward motion of the handle be continued, 110 the secondary valve 12 is opened in the manner I have already described to obtain a further flow of water. On the lowering of the parts the valve 28 is opened or thrust upward thereby permitting the upward flow 115 of oil. When the handle 42 is released after flushing has been accomplished, the valves 10 and 12, if the latter be opened, are permitted to close due to the retraction of the coiled spring 21 the plunger or piston 17 120 moving up in accordance with the rate of flow of the liquid in the chamber 15 through the by-pass passage 32. The instant the piston or plunger 17 commences to rise the valve 28 is at once closed and the oil is by-passed through the passage 32 from above 125 to below the piston or plunger 17.

What I claim is:

1. A part having a cavity and also having a port leading from said cavity combined 130

with a valve in the cavity, the valve and the cavity having convex and concave portions which are adapted to engage when the valve is closed, the valve being of triangular form 5 in cross section having ports in its several side faces, and also having an opening into which said ports lead.

2. A part having a cavity and also having a port leading from said cavity combined 10 with a valve in the cavity, the valve and the cavity having convex and concave portions which are adapted to engage when the

valve is closed, the valve being of triangular form in cross section having ports in its several side faces, and also having an opening into which said ports lead, the corners 15 of the valve being truncated.

In testimony whereof I affix my signature in the presence of two witnesses.

JOHN L. BECK.
